ATTORNEY

UNITED STATES PATENT OFFICE.

STERLING H. CAMPBELL, OF ST. LOUIS, MISSOURI, ASSIGNOR TO WESTERN RAILWAY EQUIPMENT COMPANY, OF ST. LOUIS, MISSOURI, A CORPORATION OF MISSOURI.

FLOOR CONSTRUCTION.

Application filed July 5, 1924. Serial No. 724,285.

My invention relates to floor securing means for railway cars of the general type described in Pratt United States Patent No. 1,498,119 in which the securing means does not pass through the floor sill.

The object of the present invention is to provide a clip for the above named construction which may be made from a simple form, such for example, as a disk-shaped 10 piece of sheet metal.

In the accompanying drawings which illustrate one form of floor construction made in accordance with my invention, Figure 1 is a vertical cross section through a portion 15 of a car floor to which my invention is applied; Figure 2 is a section taken in a different plane; and Figure 3 is a detail view of the clip.

One of the floor boards 5 of a railway car 20 is shown in Figure 1 as resting on a center sill 6. It will be understood, however, that my invention may be used to secure the boards to either side or center sills. Formed in the boards adjacent to the edge of the sill 25 flange are bolt holes 7 through which pass the bolts 8 for securing the boards to the sills. Each of the bolts is engaged by a nut and has a slot 10 formed in its end so that the said end may be spread to lock the 30 nut in position after it has been tightened.

Surrounding the bolt 8 between the nut 9 and the board 5 is the clip 11 which is formed of a disk-shaped piece of sheet metal with a central opening 12 for the passage 35 of the bolt. A segmental portion 13 of the disk is bent down slightly out of the plane of the body of the clip so as to conform to the angle of the under face of the flange of the sill. Two other segmental portions 14 40 are bent up substantially at right angles to

the body of the clip so as to engage with the board and hold the body of the clip out of contact therewith. It will be seen that by this construction any surface dimension of the clip from its central bolt opening 45 to its periphery is greater than the distance from the bolt to the sill and consequently the clip cannot turn into any position in which it will not engage with the sill. The portions 14 will form stops to prevent such 50 rotation when in their normal position and if straightened out to such an extent as to fail to form stops they will themselves form engaging portions for the flange of the sill.

Having fully described my invention, what 55 I claim as new and desire to secure by Letters Patent of the United States is:

1. In a device of the class described, the combination with a car sill having a flange, of a floor board supported on said sill, a 60 bolt extending through said board adjacent to the edge of the flange, and a clip on said bolt and bearing against the under face of the flange, said clip being provided with a pair of contact members for the board arranged at an angle to each other and formed by bending over portions of the clip. 65

2. In a device of the class described, the combination with a car sill having a flange, of a floor board supported on said sill, a bolt 70 extending through said board adjacent to the edge of the flange, and a clip on said bolt formed of a substantially circular piece of metal and bearing on the under face of the flange, said clip being provided with a pair 75 of contact members for the board formed by bending over segments of the clip.

In testimony whereof, I have hereunto set my hand this the 2nd day of July, 1924.

STERLING H. CAMPBELL.
